UNITED STATES PATENT OFFICE

LOUIS J. COMBE, OF LOS ANGELES, CALIFORNIA

TESTING DEVICE

Application filed May 10, 1930. Serial No. 451,471.

My present invention relates to improvements in internal combustion engine testing devices.

My primary object is the provision of a testing device for testing the cylinders of internal combustion engines in such way as to positively tell which of the cylinders are in perfect working condition.

A further object is the provision of a testing device which is designed to be suspended from the connecting rod between the radiator and the front of the body of an automobile and which has electric conductors connected therewith and provided with clips for clamping on certain of the spark plugs of the engine to short circuit such spark plugs, the clip of one of such conductors, however, being attached to a headbolt or otherwise welded on the motor block so that the working of the cylinder to which the ground clip is not attached can be ascertained without the removal of the spark plug therefrom, it being understood that the remaining cylinders are tested in the same manner.

A still further object is the provision of a testing device for this purpose that comprises a flexible member which may be readily bent so that the same can be easily positioned in the toolbox of the machine.

To the attainment of the foregoing the invention consists in the improvement herein-after described and definitely claimed.

In the drawing:

Figure 1 is a side elevation of a sufficient portion of an automobile to illustrate the application of my improvement thereon, parts being broken away and parts in section.

Figure 2 is a perspective view of the improvement per se.

Figure 3 is a side elevation of the improvement with parts in section.

In Figure 1 of the drawing the numeral 1 designates the motor of an automobile, 2 the spark plugs and 3 the brace rod which is secured between the radiator and the front of the body of the automobile.

My improvement comprises a flexible tubular head 4 of insulating material. The head 4, being flexible is susceptible to bending so that the same can be folded into a small size

which can be readily accommodated in a mechanist's work box. Secured to the top of the head, at points equidistant from the ends thereof, there is a pair of outwardly extending stems 5 which merge into hooks 6. The stems are of insulating material and are preferably centrally reinforced by wire members 5' as disclosed by Figure 3 of the drawing, the wire members having their ends embedded in the head 4 and the stems 5 may be integrally formed with the said head 4 or otherwise fixedly secured thereto. The hook-carrying stems are also flexible so that the same may be bent against the head to produce a small package when the device is not in use.

Received in the head, and tightly compressed therein there are the insulating sheathings 7 for wire conductors 7'. One of the conductors extends entirely through the sheathings in the head, and the said sheathings or insulating coverings are broken away or divided at points so that the intermediate wires 7' may be wound around and soldered to the longitudinal wire that extends entirely through the head as disclosed by Figure 3 of the drawing. The insulating sheathings for the central or intermediate wires may be formed with or otherwise secured to the head 4 as is also disclosed by Figure 3 of the drawings while the sheathings that project through the ends of the head are extended for the same length as the intermediate sheathings and all the conductor wires 7' have their ends connected to spring metal clips 8 of the ordinary construction. The sheathings or insulating covering 7, as well as the wires therein are flexible so that the same may be folded against the head when the device is not in use, and whereby the improvement may be conveniently stored in the tool box of the mechanic.

Any desired number of conductors 7' may be provided in accordance with the number of cylinders in the engine to be tested, four of such conductors and clips being disclosed by the drawing as the motor 1 is of the four cylinder type. To test say the first cylinder, three of the clips are attached to three of the spark plugs and the fourth clip is attached to one of the head bolts 9 for the motor. As

three of the spark plugs are short circuited and ground to the bolt 9 the working in the first cylinder can be readily ascertained by listening to the operation thereof without necessitating the removal of the spark plug. In a like manner by detaching other clips and grounding one of the clips the working in the remaining cylinders may be also ascertained without removing the spark plugs, it being apparent that the clips may be attached to or detached from the engine or from the spark plug without imparting an electric shock to the operator.

It is believed the simplicity of the improvement as well as the advantages of the device will be apparent and further detailed description will not be required.

Having described the invention, I claim:

A testing device for the spark plugs of internal combustion engines of automobiles, comprising a tubular head of flexible and insulating material, reinforced stems of flexible and insulating material projecting from the head and merging into hooks, a conductor wire having a sheathing of flexible and insulating material compressed in the head and having end portions extending through both ends of the head, said wire having uncovered ends, spring metal clips fixed on the uncovered ends of said wire, intermediate conductor wires connected to the first-named wire, sheathings of flexible and insulating material for said intermediate wires connected to the head, the length of said intermediate wires being approximately equal to the length of the end portions of the first-named wires which extend beyond the ends of the head, said intermediate wires having their outer ends uncovered, and spring metal clips fixed on said uncovered ends of the wires.

In testimony whereof I affix my signature.
LOUIS J. COMBE.
